UNITED STATES PATENT OFFICE

EDWIN R. KNAPP, OF SUMMIT, NEW JERSEY, ASSIGNOR TO COPPER PLATE SHEET AND TUBE COMPANY, OF NEW YORK, N. Y., A CORPORATION OF NEW JERSEY

APPARATUS FOR HANDLING SHEET METAL

Original application filed June 16, 1926, Serial No. 116,487. Divided and this application filed June 15, 1928. Serial No. 285,763.

This invention relates to apparatus for treating sheet metal, and is a division of my copending application, Serial No. 116,487, filed June 16, 1926.

5 In the said application I have disclosed a system for treating metal sheets in which the sheets are conveyed successively through the various apparatus in arched form, and are pickled, washed, dried and annealed. 10 The claims of said application are directed to the means for pickling and washing the arched sheets.

15 The present application is directed to the sheet flattening mechanism, and to auxiliary handling apparatus employed in the system disclosed in my said copending application.

An object of the present invention is the provision of means for flattening or decrowning arched sheets.

20 A further object is the provision of aligning means adapted to engage the lateral edges of an arched sheet and prevent the corners of the sheet from separating as it passes from the arching mechanism to a conveyor.

25 A further object is the provision of means for delivering arched sheets from a furnace conveyor to a decrowning mechanism.

In the accompanying drawings, I have shown one form of the invention. In the 30 drawings,

Fig. 1 is a plan view of the arching mechanism showing the aligning devices associated with the discharge end thereof;

35 Fig. 2 is a longitudinal, sectional view on line 2—2 of Fig. 1;

Fig. 3 is a plan view of the straightening rollers and the mechanism for rotating the metal sheets;

40 Fig. 4 is a side elevation of the apparatus shown in Fig. 3;

Fig. 5 is a fragmentary, longitudinal, sectional view of part of the apparatus shown in Figs. 3 and 4;

45 Figs. 6 and 7 are plan views of parts of the apparatus shown in Figs. 3 and 4;

Figs. 8 and 9 are plan views, partly in section, of parts of the apparatus shown in Figs. 3 and 4;

50 Fig. 10 is an enlarged vertical, sectional

view of certain details shown in Figs. 8 and 9;

Fig. 11 is a plan view, partly in section, of the decrowning mechanism, showing the outlet end of the furnace and showing the auxiliary conveyor between the furnace and the decrowning mechanism;

Fig. 12 is a longitudinal, sectional view on line 12—12 of Fig. 11, and

Fig. 13 is a transverse, vertical, sectional view on line 13—13 of Fig. 12.

In employing the apparatus disclosed herein, sheets are arched and passed through a furnace to anneal these. They may be previously submitted to a pickling operation, and a suitable surface coating may be applied to the sheets before annealing. This surface coating, which may be omitted if desired, may be applied by means of suitable apparatus, such as the coating machine shown in

the patent to William E. Watkins, No. 1,295,819 granted February 25, 1919. In Fig. 1 of the drawings the coating rolls are shown at 204. The aligning devices are shown in conjunction with suitable arching mechanism

70 consisting of two sets of disks 214 carried by stub shafts mounted on yokes or supporting beams 215. These disks 214 are not power driven. Their function is to hold the edges of the sheets down while the center is

75 being forced up by the larger toothed disks 216 carried by the lower supporting beam 217. The forward ends of the upper supporting beams 215 are journaled on the transverse shaft 218 and the corresponding end of the

80 lower supporting beam 217 is journaled about the transverse shaft 219. The rear ends of the upper supporting beams 215 are adjustably mounted on a transverse beam 220. A similar adjustment indicated at 221 is pro-

85 vided for the lower supporting beam 217. The shafts carrying the lower disks 216 are interconnected by a driving chain 222 and power for driving these disks is supplied

85 from a shaft of the coating machine by means of the chain 223 and gearing shown at 224 and 224a.

90 After the sheets have been arched by the action of the toothed disks 214 and 216, they are delivered to the converging guide con-

veyors 225 and 226 (see Fig. 1). These link or chain conveyors pass around pulleys 227, 228, 229 and 230. Power is supplied to the pulleys 227 and 228 from the shaft 231 driven by the chain 223. These converging conveyors serve to bring the edges of the arched sheets closer together so that the sheets can be delivered in proper form to the furnace conveyor. Screw-threaded adjusting rods 232 and 233, connected to hand wheels 234 and 235 respectively, constitute means for adjusting the distance between the ends of the converging conveyors 225 and 226 to accommodate sheets of various widths. If it is desired to have the delivery end of each of the converging conveyors extend substantially parallel with the direction of travel of the sheets, then guide rollers 236 and 237 can be arranged as shown in Fig. 1. Satisfactory results can be obtained without employing these auxiliary rollers.

The furnace conveyor constitutes a series of interconnected links, each provided with a cross-arm 238, having a number of upwardly projecting fingers 239 on each end thereof. Each arm is provided with a number of these projections 239, in order that the conveyor may be suitable for handling sheets of different widths.

I prefer to provide some means for positively feeding the sheets from the converging conveyors 225 and 226 onto the furnace conveyor. A satisfactory device for accomplishing this result comprises a pair of wheels 240 and 241, inclined at an angle to the direction of travel, as illustrated in Fig. 1. These wheels are provided with blades, and the inclined surfaces of these blades are so formed that straight-line contact is established between the blades and the edges of the advancing sheets. These wheels 240 and 241 are rotated in the direction indicated by the arrow in Fig. 2, and serve to simultaneously press down the edges of the advancing sheets and urge the sheets forward. Power is supplied to these wheels through the systems of gearing illustrated at 242 and 243. These gear systems or trains are connected to the shaft 244, which carries the furnace conveyor sprocket wheel 245. The shaft 244 is driven by the furnace conveyor. The inclined guide wheels 240 and 241 are journaled in mounting pieces 246 and 247, secured to a cross-beam 248.

The sheets are then passed through the furnace (not shown), and are then ready for the decrowning operation. At the discharge end, the furnace conveyor carries the annealed sheets into a delivery casing shown at 264, in Fig. 12. This casing encloses an auxiliary conveyor shown at 265, which serves to pick the sheets off from the furnace conveyor and deliver them to the decrowning mechanism. The delivery chamber 264 and the decrowning mechanism are all in open communication

with the furnace chamber 249. The chamber 264 is provided with a lid 264^a, which can be removed for the purpose of observing the operation of the furnace conveyor and the auxiliary conveyor 265 and making any necessary adjustments or repairs.

The decrowning mechanism comprises two sets of rollers shown at 266 and 267. The sheets are carried forward by the rollers 267 and are spread out flat as they come in contact with the upper set of rollers 266. The rollers 267 are provided near their ends with collars 267^a, best shown in Fig. 11, which prevent the sheets from traveling too much to either side. The decrowning or flattening rollers deliver the plates to the straightening rollers indicated at 268. The two sets of rollers 266 and 267 are interconnected by means of sprocket wheels and a chain 269, power being supplied to these rollers through gearing illustrated at 270 in Fig. 11.

Referring again to the auxiliary conveyor 265, I prefer to construct the track supports for this conveyor in such a manner that the conveyor can be adequately cooled. In Fig. 13, I have illustrated a track structure at 271, forming a hollow chamber through which water can be circulated for cooling the conveyor elements as they pass along the track.

In the complete process described in my pending application No. 116,487, the annealing step is followed by cooling and white pickling. As the sheets are again arched prior to the white pickling operation, it is again necessary to decrown them.

After the sheets leave the white washing apparatus and the decrowning mechanism associated therewith (not shown), they are fed between straightening rollers of the usual type, illustrated at 307 in Figs. 3 and 4. This serves to straighten the sheets in the direction of travel.

In order that the sheets may be straightened laterally, I prefer to employ an apparatus for rotating each sheet 90° and then passing the sheet forward through a second set of straightening rolls. I have illustrated such a second set of straightening rolls at 308.

The improved rotating mechanism includes a conveyor having chains 309 and 310 at each side thereof arranged to pass over sprocket wheels 311 and 312, located near the straightening rolls 307 and 308 respectively. The chains 309 and 310 carry transverse rods 313 (see Fig. 8), each provided with a plurality of collars 314. Each of the rods 313 is formed in two pieces interconnected at the center with a mounting piece 315 which carries a rotatably mounted wheel 316 having its axis at right angles to the rod. Between each set of collars 314 I have provided a bearing wheel mounted so as to be free to rotate about the rod and provided around its periphery with a plurality of small rotatably mounted disks 318 adapted to rotate about axes at right

angles to the rods 313. The wheels mounted between the collars 314 are shown at 317^a, 317^b, 317^c and 317^d. These wheels, with their disks 318, constitute what may be termed universal bearing members for supporting the sheets delivered to the conveyor by the straightening rollers 307.

It will be understood that as the conveyor moves forward in the direction indicated by the arrows *e* and *e'* of Fig. 8, the sheets are carried forward on the conveyor. Each sheet can be rotated on the conveyor by causing the wheels 317^a and 317^b to rotate in the directions indicated by the curved arrows shown near these wheels in Fig. 8, and by causing the wheels 317^c and 317^d to rotate in the opposite direction, as indicated by the curved arrows located close to these wheels in Fig. 8. The sheets then pivot about the central wheels 316 and rotate through the desired angle, depending upon the adjustment of the apparatus. After the sheet has been rotated through a predetermined angle, one edge of the sheet strikes the guide member 319 and the sheet is carried forward in proper alignment with the straightening rollers 308. After the sheets pass through these straightening rollers, they are ready for shipment.

The apparatus I prefer to employ for the purpose of causing the wheels 317^a, 317^b, 317^c and 317^d to rotate as above described, includes four belts, 320, 321, 322 and 323. These belts are arranged so that they pass under the shafts 313 and engage the wheels carried by these shafts. These belts are driven by pulleys 324, 325, 326 and 327. Each pulley is mounted on a stub shaft connected to a gear, the gears being shown at 328, 329, 330 and 331. These gears are driven by intermediate gears 332, 333, 334 and 335, carried by adjustable yokes, one of which is illustrated at 336 in Fig. 4. These intermediate gears mesh with gears 337, 338, 339 and 340, mounted on a drive shaft 341. By properly selecting the intermediate gears, the belts 320, 321, 322 and 323 can be driven at the desired differential speeds. For example, these gears can be chosen so that the belt 320 will travel forward at half the speed of the chain 309. I have illustrated this fact by showing an arrow *a*, close to the belt 320, this arrow being half as long as the arrow *e'*, which represents the speed of the chain 309. In like manner, the belt 321 can be driven at a speed equal to $\frac{3}{4}$ of the speed of the chain 309, this being represented by the arrow *b*. Since the belts 320 and 321 move at a slower rate than the conveyor chain 309, the wheels 317^a and 317^b, which come in contact with these belts, are caused to rotate as indicated by the curved arrows shown near these wheels in Fig. 8.

In like manner, the belt 322 can be caused to move forward at a speed equal to $1\frac{1}{4}$ times that of the conveyor chains, and accordingly I have shown the arrow *c* of a length equal to

$1\frac{1}{4}$ times that of the arrows *e* and *e'*. The belt 323 can be caused to move forward at a speed equal to $1\frac{1}{2}$ times that of the conveyor chains, as illustrated by the arrow *d*. Since the belts 322 and 323 move forward at a higher speed than the conveyor chains, the wheels 317^c and 317^d are caused to rotate in the reverse direction, as indicated by the curved arrows shown close to these wheels.

The belts 320, 321, 322 and 323 pass over pulleys 342, 343, 344 and 345, each carried by an adjusting block, the position of which can be changed by turning the hand wheels 346, 347, 348 and 349. The tension of the belts can be adjusted by turning these hand wheels. Two similar sets of pulleys are shown at 350 and 351, these pulleys having their centers located somewhat above the center line of the pulleys just described. These pulleys are mounted on blocks arranged so as to slide on tracks 352 and 353. Adjusting screws 354 and 355 can be turned for the purpose of bringing these two sets of pulleys closer together or separating them further apart, as may be desired. By adjusting the positions of these pulleys, it is possible to determine the number of shafts 313, the wheels of which are brought into engagement with the traveling belts. This active portion of the conveyor system is shown at *f* in Fig. 4.

In order that each of the belts may be firmly supported throughout the period of contact with the conveyor wheels, I have provided the apparatus which is shown in detail in Figs. 5, 6 and 7. Secured to each of the blocks carrying the pulleys 350 and 351, I have provided a set of blades shown at 356 and 357. Each set of blades is firmly held at one end by the pulley block associated therewith, and the free ends of adjacent sets of blades can be adjusted toward and away from each other by adjusting the positions of the pulley blocks, as described above. These free ends are supported within guide blocks shown at 358, each of which is provided with channels or passages adapted to receive the plates, as illustrated in Fig. 6.

I claim:

1. In an apparatus for handling metal sheets, means for arching each sheet, a conveyor arranged to receive the arched sheets and convey them in arched form, and a pair of rotatable aligning devices for preventing the front and rear corners of each sheet from spreading as they leave the arching means, the said aligning devices being arranged to engage only the lateral edges of the sheets.

2. In an apparatus for handling metal sheets, means for arching each sheet, a conveyor arranged to receive the arched sheets and convey them in arched form, a pair of rotatable aligning devices for preventing the front and rear corners of each sheet from spreading as they leave the arching means, and means for rotating said aligning devices,

the said devices being arranged so that they engage only the lateral edges of each sheet, and so that they press these edges downward and forward.

5. In an apparatus for handling metal sheets, means for arching each sheet, a conveyor arranged to receive the arched sheets and convey them in arched form, and a pair of aligning wheels arranged near the delivery end of the arching means with the plane 10 of each wheel at an angle to the direction of travel of the sheets, the wheels having blades with curved surfaces for engaging the lateral edges of the sheets, the surfaces being such that they make straight-line contact with the 15 edges of the sheets, and the wheels being arranged with their centers above the lines of contact with the sheets.

4. The combination of a furnace, a conveyor for carrying metal sheets through the furnace in arched form, a decrowning mechanism arranged near the delivery end of the furnace for flattening the arched sheets, and an auxiliary conveyor for transferring the 25 arched sheets from the furnace conveyor to the decrowning mechanism, the auxiliary conveyor being constructed and arranged so that it delivers the sheets to the decrowning mechanism over a smaller gap than that between the furnace conveyor and the decrowning 30 mechanism.

5. Apparatus for rotating metal sheets, comprising a set of rods, a wheel rotatably mounted on each side of one section of each 35 rod, and means for rotating the wheels on one side of said section in one direction, and for rotating the other wheels in the opposite direction.

6. Apparatus for rotating metal sheets, 40 comprising a set of rods, a wheel rotatably mounted on each side of one section of each rod, means for rotating the wheels on one side of said section in one direction, and for rotating the other wheels in the opposite direction, and a plurality of disks rotatably 45 mounted around the periphery of each of said wheels with the axes of said disks at right angles to said rods.

7. Apparatus for rotating metal sheets, 50 comprising a set of rods, a wheel rotatably mounted on each side of one section of each rod, means for rotating the wheels on one side of said section in one direction, and for rotating the other wheels in the opposite direction, and a wheel rotatably mounted at the said section of each rod with its axis at right angles to the rod.

8. Apparatus for rotating metal sheets, 60 comprising a set of rods, a wheel rotatably mounted on each side of one section of each rod, means for rotating the wheels on one side of said section in one direction, and for rotating the other wheels in the opposite direction, a plurality of disks rotatably mounted 65 around the periphery of each of said wheels

with the axes of said disks at right angles to said rods, and a wheel rotatably mounted at the said section of each rod with its axis at right angles to the rod.

9. Apparatus for handling metal sheets, 70 comprising a pair of conveyor chains, a plurality of transverse rods carried by the said chains, a plurality of wheels rotatably mounted on each side of the center of each rod, the wheels on the several rods being arranged in rows, a plurality of endless belts arranged one under each row of wheels, means for driving the conveyor chains, means for driving the belts at selected speeds, and means for supporting the belts in contact 75 with certain of said wheels.

10. Apparatus for handling metal sheets comprising a pair of conveyor chains, a plurality of transverse rods carried by the said chains, a plurality of wheels rotatably mounted on each side of the center of each rod, the wheels on the several rods being arranged in rows, a plurality of endless belts arranged one under each row of wheels, means for driving the conveyor chains, 80 means for driving the belts at selected speeds, and means for supporting the belts in contact with certain of said wheels, the said supporting means being adjustable to vary the number of wheels in contact with the belts. 85

11. Apparatus for handling metal sheets, comprising a pair of conveyor chains, a plurality of transverse rods carried by the said chains, a plurality of wheels rotatably mounted on each side of the center of each rod, the wheels on the several rods being arranged in rows, a plurality of endless belts arranged one under each row of wheels, means for driving the conveyor chains, means for driving the belts at selected speeds, and means for supporting the belts in contact with certain of said wheels, the said supporting means comprising a pair of adjustable blocks and a set of blades carried by each block and adapted 90 to intermesh with each other. 95

12. Apparatus for handling metal sheets, comprising a pair of conveyor chains, a plurality of transverse rods carried by the said chains, a plurality of wheels rotatably mounted on each side of the center of each rod, the wheels on the several rods being arranged in rows, a plurality of endless belts arranged one under each row of wheels, means for driving the conveyor chains, means for driving the belts at selected speeds, 100 means for supporting the belts in contact with certain of said wheels, the said supporting means comprising a pair of adjustable blocks and a set of blades carried by each block and adapted to intermesh with each other, 105

In testimony whereof I affix my signature.

EDWIN R. KNAPP. 130
